UNITED STATES PATENT OFFICE

167,811

BENCH

Anthony H. Schaefer, St. Louis, Mo.

Application April 18, 1951, Serial No. 14,886

Term of patent 14 years

(Cl. D15—11)

To all whom it may concern:

Be it known that I, Anthony H. Schaefer, a citizen of the United States, residing at St. Louis, State of Missouri, have invented a new, original, and ornamental Design for a Bench, of which the following is a specification, reference being had to the accompanying drawing, forming a part hereof, in which:

Fig. 1 is a perspective view of a bench showing my new design, the view being taken from the left side of the bench. The view from the right side is substantially the same as from the left side.

Fig. 2 is a rear elevational view of the bench.

Fig. 3 is an end view of the bench, taken from the right side, and

Fig. 4 is a vertical transverse sectional view taken through the center of the bench, looking toward the left end thereof.

I claim:

The ornamental design for a bench, substantially as shown and described.

ANTHONY H. SCHAEFER.
